Inventor:
IRA C. MIERLEY
By
A. M. Gallaher, Attorney

UNITED STATES PATENT OFFICE

IRA C. MIERLEY, OF DENVER, COLORADO, ASSIGNOR TO IDA B. MIERLEY, OF DENVER, COLORADO

OPERATING CURETTE

Application filed August 27, 1928. Serial No. 302,271.

This invention relates to a curette more particularly to a bone curette of the type arranged for removing exuberent or dead tissue. The invention is especially valuable for 5 mastoidal and radical sinus surgery but it is not limited to these uses as it can be effectively employed as an operating curette for removal of foreign bodies, growths, etc.

The principal object of the invention is 10 to provide a curette in which the cutting or scraping edge will always be visible to the operator so that the exact position of the edge and the operation being performed can be seen at all times.

15 Another object of the invention is to so design the curette that it will elevate and support the periosteum while the curetting operation is being carried on so that the periosteum will be entirely out of the way and will 20 not obstruct the view of the operation.

A further object of the invention is to provide a curette in which all drainage, scrapings, tissue, etc, may be immediately removed through the body of the instrument by use 25 of an aspirator.

A still further object of the invention is to so construct the handle of the curette so that the operator can at all times determine the exact position of the operating edge by the 30 position of the handle.

Other objects and advantages reside in the detail construction of the invention, which is designed for simplicity, economy, and efficiency. These will become more apparent 35 from the following description.

In the following detailed description of the invention reference is had to the accompanying drawing which forms a part hereof. Like numerals refer to like parts in all views 40 of the drawing and throughout the description.

In the drawing:

Fig. 1 is a perspective view of my improved curette.

45 Fig. 2 is an enlarged longitudinal section through the operating extremity.

The invention comprises a relatively fine metallic tube 10, slightly curved at its free extremity as shown at 11 and provided with 50 a handle 12. The handle 12 comprises a

square portion which is roughened or knurled to provide a firm secure finger grip. The handle terminates in a hose or tubing nipple 13 which receives the extremity of an aspirator tube.

55 The operating edge of the curette is indicated at 14 and cuts diagonally across the tubing 10 on a line substantially parallel to the long axis of the tube. The positioning of the edge 14 and the relatively gentle curve 11 are the principal features of the invention and allow the operator to place himself in close proximity to the zone of operation and at all times view the operating edge and its work.

60 The position of the operating edge with respect to the curved portion 11, allows the operator to force the tip of the instrument into the incision in the periosteum so that the incised edge of the periosteum will slide up 70 over the curved portion 11. This elevates the periosteum and opens the incision so that, by looking along the instrument, the operator's line of vision is along the plane of the oblique cutting edge 14. This enables him 75 to see the exact action of the operating edge at all positions of the instrument.

80 Particles of tissue and drainage from the tissues pass immediately into the interior of the tube 10 and is drawn away by the aspirator. The major portion of the actual operating is done with the upper extremity of the edge 14, allowing the lower edge to direct material into the tube. The upper extremity may be sharpened by beveling its interior 85 as indicated at 15, Fig. 2, so that the instrument can be used for a cutting operation as well as for scraping.

90 The square handle is so placed that two of its faces lie parallel to the plane of the operating edge 14 so that the operator is enabled to feel the rotation of the instrument in his fingers and knows at all times the exact facing of the curve 11 and the cutting edge 14, by sub-consciously noting the rotation of the 95 squared handle in his fingers.

99 In mastoid work and radical sinus surgery the passages for the insertion of a curette are very small and sinuous. By the use of this instrument the tube 10 acts to retract 100

the walls and curves of the passages and hold them in alignment back in the line of vision between the operator's eye and the cutting edge 14 so that the zone of operation even under the periosteum is completely visible at times.

While a specific form of the improvement has been described and illustrated herein, it is desired to be understood that the same may be varied, within the scope of the appended claims, without departing from the spirit of the invention.

Having thus described the invention, what I claim and desire secured by Letters Patent is:—

1. An aspirating curette comprising: a tube, said tube being relatively straight for the majority of its length; a gently curved portion on one extremity on said tube; and an obliquely placed operating edge on the extremity of said curved portion.

2. An aspirating curette comprising: a tube, said tube being relatively straight for the majority of its length; a curved portion on one extremity on said tube; and an obliquely placed operating edge on the extremity of said curved portion, said operating edge lying in a plane substantially parallel to the straight length of said tube.

3. An aspirating curette comprising: a tube, said tube being relatively straight for the majority of its length; a curved portion on one extremity on said tube; an obliquely placed operating edge on the extremity of said curved portion; and an internal beveled surface adjacent said operating edge acting to sharpen said edge around its extreme periphery.

4. An aspirating curette comprising: a tube, said tube being relatively straight for the majority of its length; a curved portion on one extremity on said tube; an obliquely placed, operating edge on the extremity of said curved portion; and a squared handle secured on the other extremity of said tube, said handle being hollow and communicating with the opening through said tube.

5. An aspirating curette comprising: a tube, said tube being relatively straight for the majority of its length; a curved portion on one extremity on said tube; an obliquely placed operating edge on the extremity of said curved portion; a squared handle secured on the other extremity of said tube, said handle being hollow and communicating with the opening through said tube; and a tube nipple carried on the free extremity of said handle.

6. An aspirating curette comprising: a straight tube; a gently curved extremity on said tube so as to place the operating edge thereof considerably to one side of said straight tube and an obliquely placed operating edge on the extremity of said curved

extremity, said operating edge lying in a plane parallel to the axis of said straight tube and spaced away therefrom.

In testimony whereof, I affix my signature.
